UNITED STATES PATENT OFFICE

LUKE F. KENNEDY, OF PHILADELPHIA, PENNSYLVANIA, ASSIGNOR TO GENERAL ELECTRIC COMPANY, A CORPORATION OF NEW YORK

PROTECTIVE ARRANGEMENT

Application filed August 21, 1929. Serial No. 387,523.

My invention relates to improvements in protective arrangements for electric circuits, and more particularly for circuits including the windings of electric apparatus subject to transient magnetizing currents and an object of my invention is to provide an improved protective arrangement whereby to avoid unnecessary interruptions due to transient magnetizing currents and yet maintain the desired degree of sensitivity of protection under ordinary steady state conditions. Whenever electric apparatus having windings subject to transient magnetizing currents, for example, a power transformer, is connected to a source of E. M. F. due to the momentarily great intensity of this current which may be several times normal load current, depending on the point of the E. M. F. wave at which the circuit closure occurs and the magnetic condition of the iron, the protective gear frequently operates and causes the opening of the circuit unnecessarily. Various expedients have been adopted to avoid this difficulty. Among these are permanently decreasing the sensitivity of the protective gear or setting it to operate at a point above any expected intensity of transient magnetizing current and giving the protective gear a time setting sufficiently great to avoid operation during the probable maximum period of the transient. Both these may be and often are objectionable since they involve a sacrifice of protection under normal steady state conditions. Other arrangements have involved either manually or automatically temporarily decreasing the sensitivity of the protective gear during a period supposed to be long enough for the transient condition to subside. Where these are dependent on the operator of the switch, they are of course subject to the fallibility of the human element. In some cases where automatically accomplished in connection with auxiliary switches associated with the circuit breakers the timing may be more or less indefinite. According to my invention, I propose in effect to decrease the sensitivity of the relay in accordance with a characteristic of the transient magnetizing current which is characterized by one or more harmonics of which the

second is in general predominating. In this way the time and intensity of the effect are controlled by the very factor causing the trouble.

My invention will be better understood from the following description when considered in connection with the accompanying drawing, and its scope will be pointed out in the appended claims.

In the accompanying drawing, Fig. 1 illustrates diagrammatically a protective arrangement embodying my invention, and Fig. 2 illustrates diagrammatically a modification of the embodiment of my invention shown in Fig. 1.

In the embodiment of my invention shown in Fig. 1, electric apparatus, subject to transient magnetizing currents, such as a power transformer 5, is arranged to have the circuit of its primary and secondary windings 6 and 7 controlled so as to be connected to a source of E. M. F., not shown, by suitable circuit interrupting means illustrated as a latch closed circuit breaker 8 having a trip coil 9.

For controlling the circuit breaker 8 through its trip coil, I have shown means, including a relay 10, which is arranged to control contacts 11 in circuit with the trip coil and which according to my invention is provided with means for restraining the operation of the relay connected to be energized only in accordance with a predetermined harmonic of the transient magnetizing current of the transformer 5.

As shown, the relay 10 is of the induction disk type and includes a movable member such as the disk 12 with which are inductively associated electromagnetic means, such as restraining and operating motor elements 13, 14, whose windings 15, 16 are respectively connected to be energized in accordance with the sum of and the difference between the currents in the windings 6 and 7 of the transformer 5. For this purpose the restraining winding 15 may be connected in series in a protective circuit including the secondaries of current transformers 17 and 18 connected in series for normally circulating current while the operating winding 16 is connected across points 19 and 20 in

this circuit normally at the same potential, the current transformers 17 and 18 being connected in the circuits of the power transformer windings 6 and 7 respectively. The motoring elements 13, 14 are arranged to exert on the disk 12 opposing torques whose respective directions are indicated by the arrows 3, 4. The ratio of these torques may of course be any desired value which can be governed, for example, by the relative number of turns in the windings 15 and 16.

In accordance with my invention, I provide an additional restraint which is effective during the transient magnetizing current period. As shown in Fig. 1 this may be accomplished by providing a circuit tuned to a harmonic of the magnetizing current such for example as the second harmonic. For this purpose a condenser 21 may be connected across a part, such as a half, of the restraining winding 15 and tuned therewith to form a parallel resonant circuit for such harmonic. If the power transformer 5 is subject to energization from either side then a further resonant circuit including the condenser 22 and the other half of the restraining winding 15 may be provided.

If two parallel resonant circuits are thus provided there is the probability of transformer action between the two halves of the restraining winding when energized by the selected harmonic of the transient magnetizing current with the possibility of the additional restraint being more or less nullified. In order to avoid this I may provide the relay 10', as shown in Fig. 2, with two independent electromagnetic restraining elements 23, 24, having windings 25, 26 arranged in series resonant circuits tuned to the second harmonic of the transient magnetizing current. As shown, these circuits include the condensers 27, 28, and are connected across the secondaries of the current transformers 17, 18, respectively. These restraining elements may operate for example on a second disk 12' secured to the same shaft as the disk 12 on which the main restraining and operating elements 13 and 14 operate. With this arrangement one or the other of the harmonic restraining elements 23, 24, depending on which winding of the transformer is initially excited, will exert a restraining torque assisting the torque of the restraining element 13, and proportional to the second harmonic of the transient magnetizing current in the associated power transformer winding. Inasmuch as the additional restraint is substantially dependent on the existence of the second harmonic which occurs only during the transient magnetizing period, this restraint does not affect the sensitivity of the relay 10' so that it can function with the usual sensitivity under the ordinary steady state conditions.

While I have shown and described my in-

vention in considerable detail, I do not desire to be limited to the exact arrangements shown, but seek to cover in the appended claims all those modifications that fall within the true spirit and scope of my invention.

What I claim as new and desire to secure by Letters Patent of the United States is:—

1. In combination with an electric apparatus having windings subject to transient magnetizing currents and a circuit interrupter for controlling the circuit of said windings, means for controlling said interrupter including a differential relay having a movable member, restraining and operating means for controlling the movement thereof respectively connected to be energized in accordance with the sum of and the difference between the currents of said windings, and means for additionally restraining the movement of said member only in accordance with the second harmonic of the transient magnetizing current of said apparatus. 70 75 80 85

2. In combination with an electric apparatus having a winding subject to transient magnetizing currents, and a circuit interrupter controlling the circuit of said winding, means for controlling said interrupter including a relay having a restraining winding circuit tuned to a predetermined harmonic of the transient magnetizing current of said apparatus. 90 95

3. In combination with an electric apparatus having a winding subject to transient magnetizing currents and a circuit interrupter for controlling the circuit of said winding, means including a relay for controlling said interrupter, means for restraining the operation of said relay connected to be energized only in accordance with a predetermined harmonic of the transient magnetizing current of said apparatus. 100 105

4. In combination with an electric apparatus having a winding subject to transient magnetizing currents and a circuit interrupter for controlling the circuit of said winding, means for controlling said interrupter including a relay having a movable member, operating and restraining means for controlling the movement thereof and means for additionally restraining the movement of said member only in accordance with a predetermined harmonic of the transient magnetizing current of said apparatus. 110 115

5. In combination, a power transformer, a circuit interrupter controlling the circuit thereof, means for controlling said interrupter including a differential relay having a movable member, restraining and operating means for controlling the movement thereof respectively connected to be energized in accordance with the sum of and the difference between the currents in the primary and secondary windings of said transformer and means for additionally restraining the movement of said member including 120 125 130

a restraining winding circuit tuned to the second harmonic of the transient magnetizing current of the transformer.

6. In combination with a power transformer, a circuit interrupter for controlling the circuit thereof, means for controlling said interrupter including a relay having a movable induction disk means, electromagnetic means inductively associated with said disk means and arranged to exert opposing torques thereon, and means for increasing the effect of one of said torques only in response to the second harmonic of the transient magnetizing current of the transformer.
- 10 7. In combination with electric apparatus having a winding subject to transient magnetizing currents, and a circuit interrupter controlling the circuit of said winding, means for controlling said interrupter including a relay having a movable member and electromagnetic means arranged to exert opposing torques on said member, and means for increasing the effect of one of said torques only in response to a predetermined harmonic of
- 20 23 the transient magnetizing current of said apparatus.

8. In combination with a power transformer and a circuit interrupter for controlling the circuit thereof, means for controlling said interrupter including a relay having restraining and operating elements respectively connected to be energized in accordance with the sum of and the difference between the currents in the primary and secondary windings of the transformer and means for exerting an additional restraining effect connected to be energized in accordance with a predetermined harmonic of the transient magnetizing current of the transformer.

- 40 9. In combination with a power transformer and a circuit interrupter for controlling the circuit thereof, means for controlling said interrupter including a relay having restraining and operating windings respectively connected to be energized in accordance with the sum of and the difference between the currents in the primary and secondary windings of the transformer and means for exerting an additional restraining effect connected to be energized in accordance with the second harmonic of the transient magnetizing current of the transformer.

- 15 10. In combination with electric apparatus having a winding subject to transient magnetizing currents and a circuit interrupter for controlling the circuit of said winding, means for controlling said interrupter including a relay and means responsive to a characteristic of the transient magnetizing current other than the fundamental thereof for preventing operation of the relay.

In witness whereof, I have hereunto set my hand this 17th day of August, 1929.

LUKE F. KENNEDY.
